UNITED STATES PATENT OFFICE.

CHARLES M. THRASHER, OF DOUGLAS, ARIZONA.

BAG-CLOSURE.

1,288,290.

Specification of Letters Patent. Patented Dec. 17, 1918.

Application filed April 13, 1918. Serial No. 228,394.

To all whom it may concern:

Be it known that I, CHARLES M. THRASHER, a citizen of the United States, residing at Douglas, in the county of Cochise and State 5 of Arizona, have invented certain new and useful Improvements in Bag-Closures, of which the following is a specification.

This invention relates to improvements in the closures for bags and more particularly 10 paper bags such as are employed in grocery stores, drug stores, and the like. The ordinary paper bag of the collapsible type, is devoid of any means for closing its mouth and, consequently, it is essential, after goods 15 have been placed in such a bag, to fold over the upper portion of the bag and then employ twine in securing the closure in its over-turned position. The use of twine is expensive and furthermore, no matter how tightly 20 tied, there is likelihood of loose powdered material, such for example as sugar, being wasted through the mouth of the bag. The present invention therefore has as its object to provide such a bag with a closure which 25 will in closed position effectually close and seal the mouth of the bag so as to not only effectually prevent the escape of powdered material from the bag, but also obviate the use of twine in tying the bag, thus obviating 30 waste of the material and eliminating the cost of twine. The closure embodying the present invention is, furthermore, designed to permit of such a bag being more readily and quickly sealed than is possible by the 35 ordinary method of folding over the upper portion of the bag and tying the bag with twine.

The present invention has as a further object the provision of a closure possessing 40 the advantages above pointed out and having the further advantage of being adapted to be initially housed within the mouth of the bag so as to prevent its being torn loose and so as to protect its gummed surface.

45 In the accompanying drawings:

Figure 1 is a perspective view of an ordinary paper bag provided with the closure embodying the present invention, the bag being substantially filled with material and 50 closed;

Fig. 2 is a vertical sectional view taken substantially on the line 2—2 of Fig. 1;

Fig. 3 is a vertical sectional view through the upper or mouth portion of the bag, the 55 closure flap of the present invention being housed within the bag;

Fig. 4 is a perspective view of the upper portion of the bag, the closure flap being illustrated as withdrawn from its position within the bag.

60

In the drawings, there is illustrated a bag indicated in general by the numeral 1 and of the ordinary construction, the bag including the usual front and rear walls 2 and the side plait 3 which connect these walls, the bag 65 being, of course, of that type designed to be collapsed to flat position so that a number may be packed in a small space. The mouth of the bag is indicated by the numeral 4.

The closure embodying the present invention is in the nature of a flap 5 which may either form an integral part of one of the walls 2 or it may be formed separately from the bag and attached to either wall. As is usual in the manufacture of such bags, the 75 bag is formed from a single integral blank and the lateral edges of this blank are united by overlapping the said edges and securing them together to form a seam 6 which extends vertically of one of the walls 2, and it 80 is preferable that the closure flap 5 embodying the present invention constitute a continuation of the upper portion of this wall so that the flap will be reinforced throughout its length due to the presence of the 85 double thickness of material provided by the overlapping edges forming the said seam 6. At its line of juncture with the said wall of the bag, the flap 5 is of a width equal to the width of the mouth of the bag and the side 90 edges of the said flap are inclined upwardly toward each other from the upper corners of the said wall, as indicated by the numeral 7. However, at a point between the said line of juncture of the flap with the said wall and 95 the outer end of the flap, the said lateral edges are extended in parallel relation, as indicated by the numeral 8 so that a tongue portion 9 is provided and there is applied to the inner face of the tongue portion preferably throughout the entire area thereof, a suitable coating of adhesive, indicated by the numeral 10.

As clearly shown in Fig. 3 of the drawings, which figure illustrates, however, the 105 mouth of the bag partly open so as to more clearly show the relative arrangement of the parts, it will be observed that initially the closure flap 5 is folded along its line of juncture with the wall of the bag to which 110 it is connected, so as to occupy a position within the mouth of the bag with its inner

side resting against the inner face of the said wall of the bag. Thus in the initial position of the closure flap it is effectually protected from being torn from the bag or 5 being otherwise mutilated and, furthermore, the surface to which the adhesive coating 10 is applied is protected from moisture. When it is desired to fill the bag with material, the mouth of the bag is opened and the closure 10 flap is withdrawn to assume about the position shown in Fig. 4 of the drawings, whereupon the material is introduced into the bag and after the bag has been partly or wholly filled, the mouth portion of the bag is again 15 collapsed by bringing the upper portions of the walls 2 into contact with each other, after which the adhesive carrying face of the tongue 9 is moistened and the closure 20 flap is then bodily folded downwardly along the line of juncture with the wall 2 so that said flap will wholly overlap the outer face of the other wall of the bag and become united thereto by the said adhesive. As the 25 closure flap at its line of juncture with the wall of which it forms an extension, is of a width equal to the width of the mouth of the bag, the mouth of the bag will be effectually closed so as to prevent waste of powdered material from the corners of the 30 mouth. Furthermore, inasmuch as the flap forms a part of that wall of the bag which is provided with the seam 6, the flap is effectually reinforced and stiffened. It will

be evident that by the employment of the closure above described, the use of twine is 35 entirely obviated.

Having thus described the invention, what is claimed as new is:

As a new article of manufacture, a bag having side walls and connecting side plaita, 40 the blank from which the bag is formed having edge portions overlapping and secured together to form a seam extending vertically of one of the walls, and a closure for the mouth of the bag comprising a flap 45 constituting an extension of the seam-carrying wall whereby the flap will be reinforced by the presence of said seam, the flap at its line of junction with the seam-carrying wall being of a width equal to the width of the 50 mouth of the bag and the free end of said flap being reduced in width, the inner face of the reduced end of the flap being coated with an adhesive material and said flap when the bag is open being foldable downwardly within the mouth thereof to house and protect the adhesive material, the wide end of the flap being adapted to extend across the mouth of the bag when the latter 55 is closed and the reduced end of said flap 60 being adapted to overlap the outer face of the other wall and be secured thereto by said adhesive material.

In testimony whereof I affix my signature.

CHARLES M. THRASHER. [L. S.]
